UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

SHEET-METAL-WORKING MACHINE.

1,246,437.

Specification of Letters Patent. Patented Nov. 13, 1917.

Application filed January 29, 1916. Serial No. 75,022.

To all whom it may concern:

Be it known that I, PETER KRUSE, a citizen of the United States of America, residing in the borough of Brooklyn, county of Kings, city and State of New York, have invented certain new and useful Improvements in Sheet-Metal-Working Machines, of which the following is a specification.

This invention relates to improvements in machines for forming tubes of sheet material, and more particularly tubular can bodies from sheet metal.

The present invention provides a machine capable of running accurately and smoothly at high speed. The invention further provides a machine wherein the construction is simple and durable, and wherein shocks are minimized.

Other advantages and improvements will be hereinafter set forth.

Two embodiments are illustrated in the accompanying drawings with reference to which the invention will be more fully explained. In said drawings,—

25 Figure 1 shows one embodiment in side elevation, and in partial vertical section;

Fig. 2 is an end view, partially in vertical section, of the construction shown in Fig. 1;

30 Fig. 2^a is a diagrammatic view illustrating the action of the slide rod, lever and crank shown in Fig. 2.

Fig. 3 is a sectional view of a portion of the machine on the line III—III, Fig. 2;

35 Fig. 4 is a view similar to Fig. 2 showing a second embodiment of the invention.

Fig. 5 is a perspective view (with parts broken away and in section) illustrating details of the expanding horn.

In the drawings the tubular-body forming mechanism is shown as embodied in a sheet working machine comprising an automatic feed mechanism, and certain devices for performing operations upon the sheets, such as notching and flanging as set forth, for example, in my United States Patent #1,081,050 dated Dec. 9, 1913. The automatic feed mechanism, notching and flanging mechanisms, could, however, be omitted.

40 A designates a horn around which the tubular bodies are formed. The horn may be of any suitable construction, and is preferably of the expanding type. The sheets are wrapped around the horn by means of a pair of wings or folders B B'. As shown in the drawing, the wings are pivoted to a bracket

b attached to the main frame of the machine. The wings B B' swing around and away from the horn to wrap a sheet around the horn, and to allow the feed of another sheet to the folding mechanism. In a high speed 60 machine it is desirable that the change of direction of motion be gradual as the wings approach the ends of their opening and closing movements and shock thereby diminished or avoided. It is furthermore desirable that there be something in the nature of a dwell in the movement of the wings at their open position. This relative dwell is desirable to permit of the feeding of the 65 sheet upon the horn, and the feeding of the 70 previously formed tubular body off the horn, during the interval that the wings are beyond the line of advance of the sheets, i. e., the flat position of the sheets.

In order to operate the wings B B' in the 75 manner described, the wings are connected to a lever C through suitable connecting rods c c, the lever C being suitably pivoted on a pin c¹ and being actuated by a crank D through suitable connecting mechanism. As 80 shown in the drawings, the crank D may be in the form of a pin attached to the face of a gear d on a shaft d¹, the gear d meshing with a gear d² on a drive shaft d³ which may receive motion through a pulley d⁴. 85

The means connecting the lever C and the crank pin D is preferably in the form of a slide rod d⁵ (Fig. 2) sliding in a bearing d⁶, and having a pin d⁷ at one end working in a slot c¹ in the lever C, and connected at its 90 outer end to the crank pin D by means of the link d⁸. In the embodiment shown in Fig. 2, one of the connecting rods c may be connected directly to the lever C, and the other indirectly connected thereto through the pivoted lever c³, the lever c³ having a slot c⁴ therein within which works a pin c⁵ upon the lever C. The lever c³ is provided with a counterweight c⁶, so as to equalize the momentum or inertia thereof with the lever C. 95

The crank pin D imparts to the rod d⁵ a reciprocating motion which in in its to and fro movement is first slow, then accelerates, and then loses speed, becoming again slow. The 105 pin d⁷ sliding within the slot c¹ of the lever C produces a variable moment, the moment being greater at the beginning of the upward movement of the rod d⁵, and vice versa. The rod d⁵ therefore moves the lever 110

G at a more rapid rate when the moment is small than it does when the moment is greater. Due to the movement of the crank pin D, and of the pin d^7 sliding in the slot c^1 , the downward movement of the wings 5 B B' is relatively slow at first, and accelerating as the wings close upon the horn, the movement being progressively slowed and stopped as the wings reach their final position on the horn. Vice versa, the opening 10 movement of the wings is rapid until they reach a point above the line of feed of the sheets, whereupon the movement becomes relatively slower, so that the wings B B' 15 are above the line of feed of the sheets a period relatively longer than that when the wings are below the line of feed of the sheets. The throw of the lever C is preferably greater above a horizontal line running 20 through the pivots c^7 c^7 , than below said line, which arrangement conduces to the relatively greater length of time that the folders B, B' are above the line of feed of the flat sheets than below said line. The 25 feeding of the sheets to the horn is facilitated by the relatively greater time interval in which the wings are above the line of feed of the sheets.

In forming tubular bodies from sheets 30 having flanges, and adapted to form a "locked" seam, it is desirable that the wings, in the final closing movements, at least, shall perform their final closing movements at either substantially the same time, or at 35 times slightly different, one moving slightly ahead of the other, one of the wings, as for instance the wing B' which acts on the side of the sheet having the outwardly projecting flange, wrapping the flanged edge of 40 the side of the sheet against which it acts around the horn in such manner that the side of the sheet having the inturned flanged edge may lock on the outside of the edge of the sheet having the out-turned flange. By 45 referring to Fig. 2 it will be seen that the pin c^5 slides toward the pivot of the lever c^3 until the pin c^5 is in line with the pivots of the lever C and c^3 , and then slides away from the pivot of the lever c^3 . At the final closing 50 moments of the wings, the wing B' moves a little more rapidly to its final position than the other wing, by reason of the fact that the angular movement at this time of the lever c^3 is greater than that of the 55 lever C.

However, by moving the wings at equal rates during their final closing movements, it is possible to lock the flanges by reason of the "spring" or resiliency of one of the 60 flanged edges of the sheet, this being effected by the adjustment of the tips b^2 b^2 of the wings so that if the wings move at substantially the same rate during the final closing movements this is sufficient.

65 By referring to Fig. 2 it will be seen that

the downward movement of the levers C and c^3 is such that at the end point of the movement the movement of the wings is substantially equal, the wing B', however, approaching the equality of speed of movement at a slightly greater rate than the wing B. In Fig. 2 the positions of the crank D, levers C and c^3 , and folders or wings B, B', at different instances, are indicated by the numerals 1, 2, 3, etc.

Just after the flanges are locked by the wings B B' the horn may be expanded by a wedge-piece f coming into contact with an expander slide a^2 which acts to spread the portions a^3 a^3 of the horn, the expanding slide a^2 having cam faces a^{10} which act against studs a^{11} on the pivoted portions a^3 , a^3 of the horn. A spring a^{12} pushes the expander slide a^2 to normal position, where the studs are not acted on by the cam faces a^{10} . See Fig. 5. The wedge-piece f is carried by a crosshead F which is reciprocated by an eccentric and eccentric connecting rod f^3 , the eccentric being fixed upon the shaft d^3 . An eccentric sleeve f^4 may be provided on the eccentric connecting rod around the pin f^5 on the crosshead F for the purpose of adjusting the upward throw of the crosshead. The wedge-piece f is vertically adjustable on the crosshead to time the action 95 of the wedge-piece on the expander. This may be accomplished by a rod f^7 having inclined planes f^8 on one end which fits within a slot f^9 in the wedge-piece f . By moving the rod f^7 in or out, the height of the wedge-piece f may be adjusted.

The crosshead F also carries the hammer or bumper G, which, at the instant the horn is expanded, meets the interlocked flanges of the sheet wrapped around the horn and drives them within a groove a^5 in the horn, thus forming the lock seam. After the seam is formed, the horn collapses and the formed tubular body may be ejected from the horn by a feed bar H.

During the feeding of sheets to the horn, it is preferable to displace or lower the horn. This may be effected by mounting the horn A upon a slide a^7 which is normally pressed upward by a spring a^8 . When a sheet is fed to the horn the slide a^7 and horn A are pulled downward by a cam a^9 acting upon a bell-crank lever a^{10} connected to the slide a^7 by a link a^{11} .

It is desirable to hold the sheet in place between the horn and the underside of the bracket b during the time that the horn is displaced. This may be accomplished by a presser I which may be conveniently mounted in the underside of the bracket b. This presser presses the sheet against the horn and holds it until the horn rises and presses it against the underside of the bracket and grips it.

As shown in Fig. 4, the lever C may be

connected to the crank pin D by means of a connecting rod D^9 and a pin d^{10} . Both the connecting rods $c\ c$ may, as illustrated in the embodiment shown in Fig. 4, be connected to the lever C. In this construction the action of the lever C may be such as to produce a differential action of the folders B and B' during the final closing movements thereof. The movements of the folders B B' may, however, shade off into a substantially equal rate of movement, as explained in connection with the embodiments shown in Figs. 1 to 3 of the drawings. The throw of the lever C is preferably greater above a horizontal line running through the pivot c' , than below said line, by which arrangement the folders B, B' are in a position above the line of feed of the flat sheets a relatively greater length of time than they are below such line of feed. The movement of the crank pin D also contributes to this end.

While I have illustrated and particularly described several embodiments of my invention, the inventive ideas are capable of other and different mechanical expression.

What I claim is:—

1. A machine for forming tubular bodies from sheet-material, comprising a horn, a folder, and means for actuating said folder, said means comprising a lever, two shafts at substantially right angles connected by bevel gears, a crank pin on the face of one of the gears, a connecting rod connected to said crank pin adapted to oscillate said lever to actuate said folder, a hammer adapted to press the folded ends of the sheet against the horn, and means on said other shaft for actuating said hammer.

2. A machine for forming tubular bodies from sheet-material, comprising a horn, a pair of folders, and means for actuating said folders, comprising a lever mounted upon a fixed pivot, connections between said lever and folders, said connections comprising a connection between said lever and one of said folders and a lever actuated by said first-named lever and a connection between

said second-named lever and the other of said folders.

3. A machine for forming tubular bodies from sheet-material, comprising a horn, a pair of folders, and means for actuating said folders, comprising a lever mounted upon a fixed pivot, connections between said lever and folders, said connections comprising a lever actuated by said first-named lever and having a sliding connection therewith, and a connection between said second-named lever and one of said folders.

4. A machine for forming tubular bodies from sheet material, comprising a horn, a pair of folders, and means for actuating said folders, said means comprising a lever, and connections between said lever and folders, said connections comprising a lever actuated by said first-named lever, and a connection between said levers adapted to produce a differential movement of the second-named lever during a portion of the movement thereof corresponding to the latter part of the closing movements of the folders.

5. A machine for forming tubular bodies from sheet material, comprising a horn, means for displacing the horn during the feed movement of sheets to the horn, a pair of folders, and means for actuating said folders, said means comprising a lever, connections between said lever and folders, and means for oscillating said lever.

6. A machine for forming tubular bodies from sheet material, comprising a horn, means for displacing the horn during the feed movement of sheets to the horn, a folder, and means for actuating said folder, said means comprising a lever, connections between said folder and lever, and a crank for oscillating said lever.

In witness whereof, I have hereunto signed my name in the presence of two subscribing witnesses.

PETER KRUSE.
